UNITED STATES PATENT OFFICE.

CHARLES P. TURNER, OF NEW YORK, N. Y.

ELECTROLYTICAL APPARATUS.

SPECIFICATION forming part of Letters Patent No. 578,171, dated March 2, 1897.

Application filed February 8, 1896. Serial No. 578,542. (No model.)

To all whom it may concern:

Be it known that I, CHARLES P. TURNER, of New York, in the county and State of New York, have invented a new and Improved 5 Electrolytical Apparatus, of which the following is a full, clear, and exact description.

The invention relates to electrolytical apparatus for the separation of metals from their ores; and the object of the invention is to provide a new and improved apparatus which is simple and durable in construction and arranged to separate the precious metal from the ore and without mixing the gangue with the electrolyte.

15 The invention will be fully described hereinafter and its novel features pointed out in the claims.

Reference is to be had to the accompanying drawings, forming a part of this specification, 20 in which similar characters of reference indicate corresponding parts in all the figures.

Figure 1 is a sectional side elevation of the improvement. Fig. 2 is a perspective view of the ore-containing receptacle, and Fig. 3 25 is an enlarged side elevation of the same with part of the lining omitted and showing transverse partitions in section substantially on the line 3-3 of Fig. 2.

The improved apparatus is provided with 30 a tank A, adapted to contain the electrolyte B, and supporting a cathode C, connected with a dynamo D or other source of electrical supply, the dynamo being also connected with an anode in the form of a receptacle E, 35 adapted to be suspended in said tank A or removed therefrom by a suitable hoisting device F. The receptacle E is preferably made in the form of a cage having its frame composed of metallic bars E', covered with a suitable 40 fabric E², such as hair, cotton, or linen cloth, and of a fineness that will keep the granulated or pulverized ore from dropping or sifting through the lining into the electrolyte B. The lining, as well as the metal 45 bars E', is covered by a conducting substance, preferably a carbon mixture, which will preserve the metal and cloth from corrosion, and at the same time is a good conductor of electricity.

50 Within the receptacle I may arrange a series of transverse partitions, as shown at E⁵. (See Fig. 3.)

The receptacle E may also be made of other material than metal and coated with an anticorrosive substance or material and an 55 outer coating of carbon or other conducting material, so that a connection may be made with the material or ore contained in said 60 crate and the electrolyte and complete the circuit through said electrolyte and metallic conductors to the dynamo and to the cathode, thereby forming a perfect circuit.

The receptacle above described may be supported by top, sides, or bottom for the 65 purpose mentioned.

The receptacle E is provided at its ends with ears E³, adapted to be engaged by the hooks F' of the hoisting device F, so as to conveniently attach or detach the hoisting device to or from the receptacle, the latter 70 being also provided on its bottom with an eye E⁴ for conveniently emptying the receptacle of the gangue after the electrolytical process is completed and the receptacle has been removed from the tank.

75 Now it will be seen that by the arrangement described the ore contained in the receptacle E is subjected to the electrical action of the current, so that the precious metal is taken up by the electrolyte B and deposited on the 80 cathode C in the usual manner.

It will also be seen that by the arrangement described the gangue remaining in the receptacle E is not liable to pass into the electrolyte, and consequently the gangue is always 85 kept separate from the electrolyte and may be readily removed upon removing the receptacle E from the tank A after the process is completed.

The purpose of the partitions E⁵ is to divide 90 the ore to be treated into smaller lumps or masses, thus facilitating the access of the electrolyte to the center of each lump, also preventing too close packing of the ore.

Having thus fully described my invention, 95 I claim as new and desire to secure by Letters Patent—

1. An electrolytical apparatus, comprising a tank adapted to contain the electrolyte and provided with an electrode, and a transversely-partitioned receptacle adapted to contain the ore and to be set in said tank, the said receptacle having perforated walls and being made of a non-conducting fabric coated

with a conducting substance, and means for connecting said substance with a source of electrical supply, so as to form the other electrode, substantially as described.

5. 2. An electrolytical apparatus, provided with an anode consisting of a non-conducting receptacle coated with an anticorrosive substance and provided with an outer coating of a conducting material, and means for connecting said outer coating with the positive pole of a source of electrical supply, substantially as shown and described.

3. A receptacle adapted to constitute the anode of an electrolytical apparatus, said receptacle consisting of a frame, a lining secured to said frame and forming the walls of the receptacle, the lining being made of a non-conducting open fabric so as to afford perforations for the entrance of the electrolyte, and 20 a conducting-coating for the lining, said coating being provided with means for connecting it with the positive pole of a source of electrical supply, substantially as described.

4. A receptacle adapted to constitute the

anode of an electrolytical apparatus, consisting of bars forming a frame, an open-meshed or porous non-conducting fabric secured to said bars and forming the walls of the receptacle, and a conducting substance on the outer surface of said walls, said substance being 30 provided with means for connecting it with the positive pole of a source of electrical supply, substantially as described.

5. A receptacle adapted to constitute the anode of an electrolytical apparatus, consisting of bars forming a frame, an open-meshed or porous fabric secured to said bars and forming the walls of the receptacle, an anticorrosive coating on the outer surface of said fabric, and a conducting substance on said coating, said substance being provided with means for connecting it with the positive pole of a source of electrical supply, substantially as described.
